UNITED STATES PATENT OFFICE.

BERTHA G. HUDLOW, OF LONG BEACH, CALIFORNIA.

DESIGN FOR AN ELECTRIC LAMP.

Application filed February 19, 1924. Serial No. 8,679. Term of patent 3½ years.

To all whom it may concern:

Be it known that I, BERTHA G. HU-DLOW, a citizen of the United States, residing at Long Beach, in the county of Los Angeles and State of California, have invented a new, original, and ornamental Design for Electric Lamps, of which the following is a specification, reference being had to the accompanying drawing, forming a part thereof.

The figure is a perspective view of an electric lamp showing my new design.

I claim:

The ornamental design for an electric lamp, as shown.

BERTHA G. HUDLOW.
